METHOD AND MEANS FOR REGULATING
TEMPERATURE IN ORE ROASTING FURNACES

David Leo Cramp, Kirkland Lake, Ontario, Canada, assignor to Lake Shore Mines, Limited, Kirkland Lake, Ontario, Canada

Application July 15, 1939, Serial No. 284,586

5 Claims. (Cl. 266—20)

This invention relates to a method and means for air-cooling parts of an ore roasting furnace of the single hearth type and for thereby regulating the temperature within the furnace.

While it has previously been proposed to employ air in combination with water for cooling the rabble arms in a single hearth furnace of, for instance, the Edwards' type, it has not previously been suggested, so far as applicant is aware, to employ air exclusively for the cooling of rabble arms and other parts of such single hearth furnaces. Moreover, it has not previously been proposed to use air cooling means for such furnace parts for the purpose of regulating the temperature of the charge within the furnace. It will be recognized that the use of water cooling arrangements for regulating the inner temperature of the furnace is impractical since, in order to maintain a water circulation, the temperature thereof must be kept below boiling. Thus the temperature of the parts in contact with the water will be maintained below a certain maximum degree, which is too low to be of utility in regulating the roast temperature in the furnace.

The object of the invention is to provide a method and means for air cooling parts of a single hearth roasting furnace, including the rabble arms, hearth and arch, and for regulating the temperature of the roast within the furnace by means of the air cooling means.

The invention will be described with reference to the accompanying drawing in which

Figure 1 is a sectional elevation of a single hearth furnace to which is applied an air cooling means in accordance with the invention,

Figure 2 is an enlarged plan of an air circulation fitting for the rabble arm shaft, and

Figure 3 is an enlarged sectional elevation of the fitting illustrated in Figure 2.

In the drawing, 1 is an ore roasting furnace having a single hearth 2 composed of hollow tiles 3 and a metal arch 4 in which are formed a plurality of interconnected ducts 5. Rotatably mounted on the frame 6 of the furnace are rabbles 7 having vertical spindle shafts 8 on the lower end of which within the furnace are arms 9. Each shaft and arm are hollow, an inner partition 10 being provided and extending from adjacent the end of the arm to a point just above the arch. Thus, air admitted to the hollow shaft may circulate down one side of the shaft and arm within the furnace and up the other side of the shaft and arm, an outlet 11 being provided therefor outside the furnace. An air outlet plug

11' for admitting combustion air within the furnace may also be provided.

Each shaft 8 is rotated by means of a bevel gear 12 having a bearing 12' fixed to the top of the shaft and bevel pinion 13 meshing with gear 12 and fixed to a horizontal driving shaft 14.

Air is supplied to the hollow within each shaft 8 through a cylindrical two-part fitting 15 having an annular downwardly projecting seat 16 bearing upon an annular depressed seat 16' on the top of bearing 12'. The fitting 15 is of a weight that its seat 16 provides a substantially air tight seal with the bearing 12'. The fitting 15 is provided with an air duct 17 leading from its side surface to the hollow within the shaft 8. The duct 17 has a nipple 18 at the surface of the fitting whereby an air hose connection 19 may be attached thereto. The hose connection is also attached to a nipple 20 in an air header 21' served by a pipe 21 leading from a housing 22 within which is mounted a fan 23.

The fitting 15 is provided on its upper surface with a groove 24 adapted to accommodate passage therethrough of the horizontal shaft 14. The shaft 14 thus serves to maintain the fitting 15 in its position on top of the bearing 12'.

An air pipe 25 leads from the fan housing 22 to a header 25' adjacent the hearth 2 and an air connection 26 leads therefrom to the hollow within the hearth at one end thereof. The other end 30 of the hearth may be open to the atmosphere to provide an air outlet.

Another air pipe 27 leads from pipe 25 and is provided with branches 28 and 29 leading to headers 28' and 29' adjacent either end of the arch 4. Air connections 30 and 31 connect the respective branches to ducts 5. Air outlets 32, for discharging air outside the furnace, and outlet plugs 33, for discharging air, as required, within the furnace, are provided in the arch. 40

Draft gauges 34 whereby the air pressure may be controlled are provided.

Dampers 35 for controlling the air flow are provided in pipes 21, 25, 28 and 29.

In operating the furnace in accordance with the invention, while roasting a charge of sulphide ore concentrate, a volume of air is circulated through the rabbles and, if required, through the arch, to maintain a predetermined temperature within the furnace. The roasting temperature of sulphide ores is approximately 1050° F., such temperature being taken at a point above the charge and at a central portion of the furnace. This temperature must be maintained for an effective roast. The normal temperature of a 55

roasting charge, if not controlled, will vary greatly and substantially in accordance with the sulphur content of the ore concentrate forming the charge. Thus, a concentrate containing 25% and upwards of sulphur is usually regarded as a self-roasting concentrate, the sulphur content providing the necessary fuel for roasting the ore. As the percentage of sulphur content rises, the additional fuel thus provided increases the 5 temperature of the charge unless means are provided to control the same. As the percentage of sulphur content decreases, the temperature of the charge also decreases unless additional fuel is provided. A concentrate containing below 10 25% sulphur is not usually regarded as self-roasting when water-cooled rabbles are employed since the rabbles must be maintained at so low a temperature for circulation purposes that the combustion ceases.

15 20 In accordance with the invention, the temperature of the charge, which, as previously set forth, is substantially dependent on the sulphur content of the charge, is taken at a suitable point in the furnace, which point is usually above the roasting charge and centrally of the furnace. Such temperature is then raised or lowered by 25 decreasing or increasing the volume of air circulated through the rabbles and, if necessary, the arch, whereby the correct roasting temperature 30 of approximately 1050° F. is maintained.

The present invention permits the self-roasting of ore concentrates containing as low as 19% sulphur since a much higher temperature of rabbles than that possible with water-cooling may be maintained by decreasing the volume of circulating air while yet providing sufficient cooling air to prevent burning of the rabble arms.

In the roasting of concentrates containing such a low sulphur content, it may not be necessary 40 to circulate cooling air through the arch, either for the purpose of controlling the furnace temperature or of preventing injury to the arch itself.

When a charge containing a high percentage 45 of sulphur is being roasted and the furnace temperature tends normally to increase, a greater volume of air is circulated through the rabbles and the arch to maintain a lower temperature.

The provision of a cooling air circulation in 50 the arch, in addition to serving to control the furnace temperature, is also advantageous from a maintenance standpoint since possible injury to the arch and supporting structure from overheating is greatly lessened thereby.

55 The air cooling of the hearth is important in that it makes it possible to reduce the tempera-

ture of the roasted charge quickly. If no attempt is made to hasten the cooling rate of the roasted charge, a long distance of travel for the charge through a cooling zone is necessary to permit a sufficient drop in the temperature of 5 the charge. Thus, the overall length of the furnace is lessened by the omission of a special cooling zone, and the initial cost of installation of the furnace decreased accordingly.

I claim:

1. In the roasting of sulphide ores in a single hearth furnace, the method of regulating the furnace temperature comprising circulating air through the rabble arms and arch of the furnace, and regulating the volume of air so circulated to 15 maintain a predetermined temperature inside the furnace.

2. In an ore roasting furnace having a single hearth, a hollow metal arch and rabble arms therein, means for circulating cooling air 20 through said arch and rabble arms and means for regulating the volume of air so circulated.

3. An ore roasting furnace comprising a single hollow tile hearth, a hollow metal arch, hollow rabble arms within the furnace, means for 25 circulating cooling air through said hearth, arch and rabble arms, and means for regulating the volume of air so circulated.

4. In an ore roasting furnace having a single hearth and a rotatable vertically mounted hollow shaft carrying a hollow rabble arm, means for circulating cooling air through said shaft and rabble arm including a stationary fitting 30 surmounting said shaft and having an air channel therein communicating with the hollow in 35 the shaft, said fitting having a seat adjacent the top of the shaft and being of sufficient weight to maintain an air-tight engagement with said seat.

5. In an ore roasting furnace having a single 40 hearth, a vertically mounted hollow shaft carrying a hollow rabble arm, a gear having a bearing fixed to the top of the shaft and a horizontal driving shaft having a gear adapted to rotate said first gear and vertical shaft, means for 45 circulating cooling air through the vertical shaft and rabble arm including a substantially cylindrical stationary fitting surmounting the vertical shaft and having an air channel therein communicating with the hollow in the shaft, 50 said fitting also having a groove in its upper face through which said horizontal shaft extends and a seat on its lower face engaging said gear bearing.
